UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING YOKE.

1,252,296.

Specification of Letters Patent. Patented Jan. 1, 1913.

Application filed September 2, 1915. Serial No. 48,586.

To all whom it may concern:

Be it known that I, JOHN F. O'CONNOR, a citizen of the United States, residing at Chicago, in the county of Cook and State of Illinois, have invented a certain new and useful Improvement in Draft-Rigging Yokes, of which the following is a full, clear, concise, and exact description, reference being had to the accompanying drawings, forming a part of this specification.

This invention relates to improvements in draft rigging yokes.

In the present operation of railroad cars, much difficulty is experienced in the upkeep of the couplers, the shanks of which wear very rapidly where the same slide upon the carry-iron. Some of the reasons for this unusual excessive wear of the draw-bar or coupler shanks are, the increased weight of the coupler head during recent years and the increased length of the coupler shank, both of which facts have resulted in the end of the coupler beyond the carry-iron being overbalanced. Consequently, the coupler and its shank tends to tilt with the outer end downward and the butt end upward. This causes excessive wear on the coupler shank in its sliding movements over the carry-iron.

The object of my invention is to provide a simple and efficient arrangement which will overcome the defects above indicated.

In the drawing forming a part of the specification, Figure 1 is a longitudinal vertical sectional view of a car draft rigging showing my improvements in connection therewith. And Fig. 2 is a horizontal sectional view of the structure shown in Fig. 1.

In said drawing, 10-10 denote the draft sills to which are secured the rear stops 11 and front stops 12. Mounted between the sills is a shock absorbing device which I have indicated as of the friction gear type at 13, the latter having associated therewith a front follower 14. The draw bar or coupler 15 is shown as of standard type and is operatively connected with the shock absorbing mechanism by a yoke designated generally by the reference A, to which it is connected by a coupler key 16, the latter extending through and being slidable in slots 17 in the draft sills. The gear and yoke are supported by a saddle plate 18, and the draw bar is upheld by a carry-iron 19.

The yoke A is shown as of the two part type, although it will be understood the

same is merely illustrative. As shown, the yoke A comprises two preferably like members 20-20, each of which has an upper arm 21, lower arm 22, rear connecting portion 23, and a half hood at the forward end formed by the forward ends of said arms 21 and 22, and a side wall 24. The side walls 24 of the two members 20-20 are provided with slots 25 to receive the coupler key 16, said side walls being also suitably reinforced by ribs 26. The side walls 24 are forwardly extended as indicated at 27, said walls being preferably outwardly flared from the coupler shank as clearly indicated in Fig. 2, to permit radial movements.

Each yoke member 20 also has an upper wall or flange 28 and a lower wall or flange 29 extended forwardly of the hood, the former having a curved portion 30 and a horizontal portion 31, and the latter an upwardly and outwardly curved portion 32 and horizontal portion 33. As clearly indicated in the drawing, the upper and lower flanges 28 and 29 overlap the upper and lower sides of the coupler shank and are extended forwardly to a point preferably slightly forward of the outer edge of the carry-iron 19 when the parts are in normal position.

From the preceding description, it will be seen that the shank of the coupler is supported by the yoke between the points a-a, and does not come into contact with the carry-iron, and since, in the arrangement as shown no substantial amount of relative movement is provided for between the coupler and yoke, the coupler shank receives practically no wear. On account of the extended support for the coupler shank, tendency of the coupler to tilt is prevented, even when pulled out to the maximum extent under draft.

Not only does the foregoing described arrangement materially increase the life of the coupler shank but the life of the carry-iron is also increased since it is not subjected to as severe wear as in those constructions where the coupler is permitted to tilt and ride directly thereon.

I claim:

1. A yoke of the character described comprising two members, each of which is provided with a forwardly extended flange arranged to engage the under side of a draw bar shank in front of the butt of the draw

bar and thereby support the draw bar and prevent it from coming in contact with a carry iron.

2. A yoke of the character described comprising two members, each of which is provided with a half hood arranged to fit over a draw bar butt, each of said members being also extended forwardly of the hood and

provided with integral flanges adapted to overlap a draw bar shank, whereby a draw bar is adapted to be supported by said flanges and the latter rest upon a carry-iron. 10

In witness that I claim the foregoing I have hereunto subscribed my name this 31st day of July, 1915.

JOHN F. O'CONNOR.
